UNITED STATES PATENT OFFICE

HENRY E. MUCHNIC, OF ATCHISON, KANSAS

RAILROAD FROG

Application filed April 20, 1929. Serial No. 356,739.

My invention relates to an improved railroad frog, having for its object a construction providing a supporting shelf at each end thereof adapted to carry and support the ends of the running rails of the track, thereby producing a better joint than heretofore obtained where the joint was made only by means of bolted angle bars.

- A further object of my invention is to 10 provide a preferably one piece frog which not only involves the provision of a supporting shelf at each end of the frog whereby to support the ends of the adjacent or abutting rails, but also to provide a frog with integral base pads or laterally disposed lobes whereby a plurality of tie attaching portions throughout the length of the frog are provided, thereby obviating the use of the usual riveted tie plates.
- 20 A further object of my invention is to provide a frog having integral gusset braces on the sides and which is tied or secured together adjacent the bottom so as to reenforce the bottom of the frog.

25 As a result, a superior rail attachment is provided having a greater security than with frogs as heretofore constructed; a better frog being obtained requiring less maintenance and involving less labor and cost.

30 The above enumerated objects and advantages, as well as other advantages inherent in the construction, will be readily comprehended from the detailed description of the drawings, wherein:—

35 Figure 1 is a plan view of my improved frog showing portions of the abutting ends of the running rails secured thereto.

Figure 2 is a longitudinal sectional view.

40 Figure 3 is an enlarged longitudinal sectional view, taken substantially on the line 3—3 of Figure 1 looking in the direction of the arrows.

45 Figure 4 is a cross sectional view taken substantially on the line 4—4 of Figure 1, looking in the direction of the arrows.

Figure 5 is a cross sectional view taken on the line 5—5 of Figure 1 as indicated by the arrows.

50 Figure 6 is a cross sectional view taken substantially on the line 6—6 of Figure 1.

Figure 7 is a cross sectional view taken substantially on the line 7—7 of Figure 1.

Figure 8 is a plan view of a portion of a cross-over frog with my invention applied thereto.

55 Figure 9 is a cross-sectional view taken on the line 9—9 of Figure 8.

Figure 10 is a plan view of one end of a self-guarded frog provided with my invention.

60 Figure 11 is a cross-sectional view taken on the line 11—11 of Figure 10.

The invention, in its specific embodiment as exemplified in the drawing, comprises the base portion 10 having a substantially flat underface to adapt it to rest on the ties. Portions of these are shown at 11 in Figure 1.

The base 10, at suitable spaced apart points throughout the length of the frog, namely at portions adapted to rest on the ties, is provided on opposite sides with integral base-pads or lobes 12, 12, the base-pads or lobes 12 being preferably of dimensions sufficient to permit the provision of a plurality of bolt-receiving apertures therein for the purpose of receiving the tie attaching elements or spikes shown at 13 in Figure 1, whereby the frog may be securely fastened to the respective ties on which it rests.

75 The toe end of the frog, shown at the left in Figure 1, is provided with an extension or supporting shelf which is shown in the sectional view Figure 4. This shelf has a base 10 extending longitudinally beyond the pads or lobes 12, 12 as shown at 14 in Figure 1; the supporting shelf being intended to extend beyond the tie 11 to which the toe end of the frog is secured a distance sufficient to overlap the adjacent tie in order to provide a suitable support for the ends of the running rails indicated at 15. That is to say, my improved 80 frog provides proper support for the ends of the rails which contact with the frog at a point intermediate of the adjacent ties and beyond the normal toe portion of the frog, as clearly shown in Figure 1. With this construction a greatly improved joint is provided, as the integral shelf reenforces the angle-bar joint between the frog and the running rails; joints which heretofore could only be made by the use of bolted angle bars.

The shelf at the toe end of the frog, namely the end at the left in Figure 1 and shown in the sectional view Figure 4, is provided with an upstanding wall or rib 16, see Figure 4, which terminates at top in a transversely disposed spacer and rail-engaging portion or head 17 of more or less thickness and of length commensurate with the spacing intermediate of the converging rail ends 15, 15 in order that the opposite ends of the spacer or head portion 17 may abut against the webs of the rails. These opposite ends of the head portion 17 are enlarged vertically and have outer arcuate surfaces at top and bottom as shown at 18, 18 in order to more or less conform with the contour of the rails at the juncture of the web portions with the rail heads and of the webs with the base of the rails, as shown in Figure 4. This transversely disposed head or spacer portion 17 is provided with a longitudinal opening therethrough adapted to receive a bolt 19 which is also disposed through registering apertures in the webs of the two rail ends, the bolt 19 constituting means for also securing the usual fish-plates on angle bars 20, 20 whereby the ends of the rails are properly attached to the end of the frog, the angle bars causing the rail ends to be firmly clamped against the opposite ends of the head or spacer portion 17 as shown in Figure 4.

The shelf at the toe end of the frog, as shown in Figure 1, is preferably provided with a series of transversely disposed spacer portions, as shown in dotted lines at 17, 17^a, 17^b and 17^c.

All of these portions are formed integral with the base 10 by means of the upstanding wall or web portion 16 and are similar in construction except that each successive head or spacer portion from the outer end of the shelf gradually diminishes in transverse length in keeping with the converging or contracted width of the frog and therefore in keeping with the distance between the running rails; the respective spacer portions are shown spaced apart lengthwise of the frog and all apertured to receive similar bolts 19 which also extend through the fish-plates or angle bars 20, 20 and the rails on each side of the frog.

In so far as the rail-engaging portions of the frog proper are concerned, my frog is of accepted standard construction and configuration, so that specific description of such portions of the frog need not be entered into.

The attaching base-pads or lobes 12, especially at the intermediate spreading portions of the frog, are preferably provided with the vertically disposed gussets or tapering ribs 21, see Figures 1 and 5.

The frog at its intermediate point portion indicated at A and extending lengthwise toward the heel end of the frog is formed as shown in Figure 5, where the base 10, adja-

cent to opposite sides, is provided with the laterally spaced apart upstanding walls 22, 22, which terminate at the top in the wheel engaging tread-portions 23, 23. The upper ends of the walls 22, 22 are in turn preferably formed integral with the bridge portion 24 formed on its upper surface with the longitudinally extending grooves or channels 25, 25, arranged on opposite sides of the intermediate longitudinal rib 26 to provide wheel-flange receiving channels.

The outer sides of the vertical walls 22, 22 are, in turn, preferably reenforced by the tapering ribs 21.

The heel end of the frog, namely the right hand end of the frog, as viewed in Figure 1, like the toe end thereof, is also provided with a supporting shelf or pad as shown at 26^a for the purpose of properly supporting the adjacent ends of the running rails 15, 15.

The general construction of this shelf or pad at the heel end of the frog is more clearly shown in Figure 6, where the base 10 has the attaching flanges or lobes 12 adapted to extend beyond the base of the rails as well as beyond the foot portions of the fish-plates or angle bars 20 whereby the ends of the rails are properly secured and clamped to the frog.

The supporting shelf 26^a at the heel portion has the base 10, at a point intermediate of the opposite sides, provided with an upstanding web or wall 27 having transversely disposed webs 28, 28 on opposite sides formed integral therewith and with the depending rail engaging sides or aprons 29, 29 which in turn are formed integral with the transversely disposed top or head portion 30.

As shown in Figure 6, the depending portions or aprons 29, 29 are offset outwardly from the sides of the head portion 30 so as to provide the shoulders 31, which extend beneath the balls or heads of the running rails 15, 15; while the depending portions 29, 29 extend flush with the webs of the rails and terminate, preferably, immediately above the rail-base.

It is apparent that a firm rail supporting structure is thus provided.

This rail spacing and supporting portion of the frog tapers gradually inwardly, namely toward the opposite end of the frog and is provided with one or more transverse holes therethrough to receive the bolts 19, which also extend through registering apertures in the running rails and angle bars 20.

At a point removed from the extension or supporting shelf of the frog, the latter is provided with one or more transversely disposed reenforcing partitions as shown at 32 in Figure 7 formed integral with the upstanding sides and with the head portion 33 which overlaps the side walls as shown. In the exemplification of the invention as shown in Figure 1, I disclose the frog at the heel provided with two transverse partitions 32,

which are both apertured to receive the bolts 19 whereby the inner ends of the fish-plates or angle bars 20 are clamped in place against the sides and beneath the head portion 33, as clearly shown in Figure 7, thereby firmly holding the adjacent ends of the running rails in place.

In Figures 8 and 9, I illustrate the application of my invention to a cross-over frog. 10 As the application of my invention is similar at each end of the frog, the showing of one corner or end of the frog is deemed sufficient. That is to say, the ends which receive the running rails 15, where the greatest strains 15 are encountered, are each provided with a rail supporting shelf 33^a formed integral with the upstanding rail engaging element 34 disposed along the inner face or side of the rails 15.

20 The rail engaging portion 34 is formed to engage beneath the head of the running rail and is undercut to receive the flange or base of the rail, as shown at 35 in Figure 9; while the top of the portion 34 is grooved at 36 to receive the flange of the wheel. The portions 34, at each end of the frog, like the rail 15, are apertured transversely to receive bolts 37 whereby the angle-bars or fish-plates 38, with the rails, are firmly bolted and clamped 25 in place. The fish-plates 38 are located to the outside of the rails and are therefore bent to fit into the outside angle of the cross-over frog as shown in Figure 8, thus serving to clamp the ends of two approach rails to the 35 frog.

The rail supporting shelf or base 33 on opposite sides, and the frog at various tie engaging points throughout, is shown provided with the integral base-pads 39, disposed laterally beyond the sides, the base-pads 39 being apertured at 40 to receive suitable spikes for fastening the frog to the ties.

In Figures 10 and 11 I illustrate the application of my invention to what is known as 45 a self guarded frog, used more particularly in switch yards, the guard being employed especially at the toe end of the frog as shown in Figure 10 where the rails 15 are arranged on the inside of the guard portions 41, 41, 50 formed integral with the extended base or rail supporting shelf 42, the rails being suitably bolted in place as more clearly shown in the cross-sectional view Figure 11. This frog, like those previously described, is also provided at suitable tie engaging points with the laterally disposed base-pads 43, apertured to receive suitable fastening means or spikes.

The frogs at points coincident with the 60 pads are provided with the supporting shelves formed integral with the frogs and with the pads, as shown in dotted lines in Figures 1, 8 and 10, thereby providing a plurality of tie attaching portions throughout the lengths of 65 the frogs, which therefore obviate the neces-

sity of employing the riveted tie plates which are usually employed.

The greatest strains or load encountered are at the point where the wheels hit the point of the frog and for that reason my improved frogs are reenforced or tied together at the bottom intermediate of its ends, thus providing a more secure structure, a frog having superior rail attachment than has heretofore been the case, and therefore a frog involving less maintenance expense.

What I claim is:—

A single piece railroad frog adapted to receive the wheels beyond the ends of the rails and provided with an integral rail supporting shelf at both ends thereof, an integral base with integral upstanding portions adapted to engage with one side of each rail, said portions adjacent to the base being adapted to receive the rail-base while the parts thereabove are formed to engage the rail-webs and off-set at the top to receive one side of the rail-heads, said portions intermediate of the top and bottoms being apertured transversely; and adjustable clamping means for the opposite side of the rails, said means being secured in place by bolts disposed through said means, the rails and the apertures in said portions.
